UNITED STATES PATENT OFFICE.

EDMUND GYBBON SPILSBURY AND SAMUEL S. WEBBER, OF TRENTON, NEW JERSEY.

HOISTING AND CONVEYING DEVICE.

SPECIFICATION forming part of Letters Patent No. 475,710, dated May 24, 1892.

Application filed October 15, 1891. Serial No. 408,848. (No model.)

To all whom it may concern:

Be it known that we, EDMUND GYBBON SPILSBURY and SAMUEL S. WEBBER, citizens of the United States, residing at Trenton, in the county of Mercer and State of New Jersey, have invented certain new and useful Improvements in Hoisting and Conveying Devices; and we do hereby declare the following to be a full, clear, and exact description of the invention, such as will enable others skilled in the art to which it appertains to make and use the same.

Our invention relates to certain new and useful improvements in tramways, and more particularly to that class of aerial wire rope or cable tramways employed for the hoisting and removal of material from one point or station to another along the line.

The object of our invention is to provide a simple, durable, and economical construction and arrangement of parts for the general purpose specified, the whole being adapted to be efficiently and quickly manipulated from the power-station by a single operator.

In the accompanying drawings, Figure 1 represents in side elevation and partial section a portion of an aerial tramway embodying our improvements. Fig. 1^a represents a like view of a continuation of said tramway, the carriage for the hoisting devices being shown as advanced along the line to the discharging-station. Fig. 2 represents, partly in section and partly in end elevation, the upper part of the power-station standard. Fig. 3 represents a similar view of the distant terminal standard. Fig. 4 represents an end elevation of the upper part of one of the intermediate standards. Fig. 5 represents a perspective of one of the open bearings for the hoisting-rope supports. Fig. 6 represents a top plan view of a portion of the tramway-carriage for the hoisting devices. Fig. 7 represents a side elevation thereof. Fig. 8 represents a central vertical cross-section through one of the pairs of tram-wheels of said carriage and the corresponding hoisting-sheave. Fig. 9 represents a side elevation of the auxiliary carriage for gathering and redistributing the removable hoisting-rope supports.

Fig. 10 represents an end elevation and partial section thereof. Fig. 11 represents, on a

larger scale, a plan view of a part of said auxiliary carriage. Fig. 12 represents a detail perspective view of the locking-catch for engaging said carriage with the hoisting-rope, 55 and Fig. 13 represents an end elevation of one of the hoisting-rope supports.

Similar numerals of reference indicate similar parts throughout the several views.

Referring to the drawings, 20 indicates a standard erected at the power-station. 21 indicates the distant terminal standard and 22 intermediate standards, all of said standards together constituting the supporting framework for the aerial tramway ropes or cables 65 23. These ropes or cables 23, preferably of wire, are at their ends securely anchored in the ground, as indicated, and are stretched as tightly as practicable over the supports, so as to sag as little as possible with the weight 70 of the hoisting-carriage. The terminal standards 20 and 21 are provided with saddles 24 25 26, having grooves within which the cables lie, and the intermediate standards 22 are provided with grooved cast-iron shoes 27 for 75 a like purpose, whereby the cables are held apart and equally spaced throughout their entire extent, but project sufficiently above the grooves to afford a sufficient bearing thereat for the passage of the tram-wheels. 80 It will of course be noted that the grooved shoes 27 of the intermediate standards are themselves spaced apart, so as not to interfere with the passage of the hoisting-carriage between them.

At the power-station is located an engine and generator 28 of any suitable type adapted to operate the sheave 29 and winding-drum 30, which are mounted and geared to revolve separately and independently of each other 90 when desired, or which, for purposes hereinafter described, may be operated simultaneously at the same rate of speed. We have not thought it necessary to specifically illustrate such gearing, as it may be readily supplied by the skilled workman.

Upon the sheave 29 is wound a few turns of a taut endless hauling-rope 31, so as to give the sheave a sufficient bite upon said rope to operate it when the sheave is revolved. 100 The outgoing portion of said hauling-rope passes over the sheave 32 of the standard 20,

thence over the barrel-rollers 33 of the intermediate supports 22, and thence over the sheave 34 of the standard 21, the return portion of the rope passing over the sheave 35 of the standard 20 and back to the sheave 29.

Interposed in the hauling-rope 31 and forming a part of it is the main-tramway carriage or carriage for supporting the hoisting devices. In Fig. 1 this main-tramway carriage is shown as at the station where the excavation is being made and from which the material excavated is to be transported. In Fig. 1^a the same carriage is shown as moved along the line to the point of dumping or discharging of the hoisting-buckets. In the form shown the carriage consists of a series of pairs of wheels 36, mounted upon journals 37, said wheels being grooved to rest upon the wire-rope tram-tracks 23. The wheel-journals 37 are connected together by tie-bars 38, through which said journals pass loosely. Upon the journals 37 are also hung loosely the vertical hangers 39, within whose lower ends are loosely journaled the hoisting-sheaves 40. These hoisting-sheaves are in like manner connected together by tie-bars 41, through which the hoisting-sheave journals pass loosely, and from the journal of each hoisting-sheave diagonal braces 42 extend to and loosely encircle the journal 37 of the next succeeding pair of tram-wheels 36. The purpose of giving this jointed structure to the framework of the tramway-carriage is to permit it to pass over the rigid supports afforded by the grooved shoes 27 without having the tram-wheels 36 leave the cable tram-tracks. In practice, however, taut the cable tram-tracks 23 may be originally, the weight of the tramway-carriage when loaded will cause more or less depression of said tracks between the points of support, as is indicated in Fig. 1. This depression would tend to cause the advance wheels of the carriage to leave the cable tram-track in passing over and beyond a support were it not for the jointed structure of the carriage, which permits the jointed sections of the carriage to accommodate themselves to the changes of level. It will be noted that the hoisting-sheaves sustaining the hoisting-bucket 43 are located immediately below the center of gravity of the corresponding tram-wheels 36, and consequently aid as weights in retaining said wheels upon the tram-tracks.

Upon the winding-drum 30 is wound a hoisting-rope 44, which, passing over the sheave 45 of the standard 20, is provided with four continuations connected at a common point 46 and supporting the corresponding hoisting-buckets 43. The function of this hoisting-rope is to permit the buckets 43 to be lowered into the excavation and filled thereat, and subsequently to hoist them out of the excavation, and to a sufficient height above the ground to be readily transported along the line to the point of discharge by the carriage supporting them. It is evident that for the purpose

of raising and lowering the hoisting-buckets the hoisting-drum 30 should be operated separately from and independently of the hauling-rope, actuating-sheave, or live-pulley 29. When, however, the buckets in the elevated position are to be transported by the hauling-rope to the discharge or dumping station, it is apparent that the hoisting-rope should be fed or paid out at the same rate of speed as the hauling-rope, in order that the height of the hoisting-buckets above the ground during transport shall remain unchanged. To this end we have provided means for engaging the hauling-rope with the hoisting-rope after the buckets have been elevated, so that as the hauling-rope is operated to carry along the buckets the hoisting-rope will be paid off from the drum 30 at a corresponding speed. The means referred to consist of a stop-block 47, fixed upon the hoisting-rope and adapted to engage with a locking catch or projection moving with the hauling-rope. In the form shown in the drawings the projection referred to is a gravity-catch 48, forked at its lower end to straddle the hoisting-rope and adapted to abut against the stop-block 47 when said gravity-catch is in the lowered position. The gravity-catch is mounted to slide freely within guides made in the frame-work of an auxiliary tramway carriage or truck connected in and forming a part of the hauling-rope. Said auxiliary carriage is provided with front and rear pairs of tram-track wheels 50, connected together by tie-bars 49, and having converging diagonal hangers 51 connected together by cross-braces 52 and supporting a grooved wheel 53, which underruns the hoisting-rope and is weighted by the depending balance 54. The gravity-catch 48 is provided with a slot or recess 55 for the engagement of a lifting-lever 56, whose actuating-cord 57 extends back along the line and is under the control of the operator, so that by pulling upon the cord the gravity-catch may be lifted out of the path of the block 47, or by releasing the cord the gravity-catch may be dropped into engagement with said block. When at the excavating-station the hoisting-buckets have been filled, they are then raised by the hoisting-rope until the block 47 abuts against, raises, and passes the gravity-catch 48, which thereupon drops again into engaging position. The stress exerted upon the hoisting-rope by the buckets and their contents is now permitted to draw back the block 47 firmly against the gravity-catch. The hauling-rope is then actuated to draw the main tramway-carriage toward the dumping-station, and during this movement of transportation the hoisting-rope moves correspondingly, being constantly paid off from its drum 30 by reason of the weight of the buckets and their contents. It is evident that because of the engagement of the block 47 and gravity-catch 48 the hoisting-rope cannot pay off or move faster than the hauling-rope; but it is limited to move at a corresponding rate of speed, so that during

transport the height of the buckets above the ground is unaltered. Arriving at the dumping-station the gravity-catch is raised and the buckets are lowered and discharged, whereupon they are again raised and returned for another load to the excavating-station.

During the movement of the carriage from the excavating-station to the dumping-station it is evident that the hoisting-rope would be liable to sag unless sustained by supports along the line. It is impracticable, however, to provide permanent supports for that purpose, inasmuch as such supports would be in the line of movement of the carriage and would obstruct its path. To obviate this difficulty we employ a series of removable supports for the hoisting-rope so located, constructed, and arranged with respect to each other and the remaining parts of the organization that, as the buckets travel toward the dumping-station, the removable supports for the hoisting-rope are successively, one after another, deposited along the line in rear of the traveling carriage at the intermediate supports, and so that on the return of the traveling carriage the said removable support will be successively gathered up and removed from the path of the returning carriage. In the form shown the removable supports consist each of a cross rod or journal 58, from which depend two cheek-pieces 59, between whose lower ends is mounted a friction-roller 60. The space between the cheek-pieces 59 is open, so as to receive the prong or forward projection of a horn 61 connected to the auxiliary hauling-rope carriage. The cross-piece or journal 58 of each of these removable supports is adapted to rest in open bearings 62, mounted upon the intermediate standards 22, as indicated in Fig. 4. These bearings occupy a corresponding position at each intermediate standard, but are spaced apart at a progressively-increasing distance with respect to each other from the most distant intermediate standard 22 to the intermediate standard nearest to the power-station—that is, assuming the open bearings at the intermediate standard 22 nearest the power-station to be a certain distance apart the open bearings of the next succeeding intermediate standard would be at a less distance apart, and so on progressively to the final intermediate standard. The length of the journal or cross-pieces 58 of the series of the movable supports varies in like manner and ratio. Assuming the removable supports to be within their respective bearings and that the hoisting-buckets and consequently the auxiliary carriage is at the remote end of the line with respect to the power-station, said carriage in moving toward the power-station would by means of the horn 61 successively take up and remove the removable supports from in front of the advancing main tramway-carriage and would arrange the removable supports upon the horn 61, as indicated in Figs. 1 and 9. To insure a closer and more compact arrangement of the removable sup-

ports upon the horn, we make the cheek-pieces 59 of the several supports of unequal length, as shown in Figs. 1 and 9, so that the friction-rollers 60 will be in different horizontal planes. On the return movement of the buckets toward the dumping-station the auxiliary carriage drops the removable hoisting-rope supports at their proper posts, the removable support having the longest cross-piece or journal being caught by the more widely-spaced open bearings of the intermediate standard through which the auxiliary carriage first passes, and so on to the last intermediate standard through which the auxiliary carriage passes.

While we have illustrated and described our improvements principally with relation to the excavation of earth and its transportation to a dumping-station, it will of course be understood that we do not restrict ourselves to such employment of the various features of our improvements, but contemplate the employment of the several devices for analogous objects and indeed for all useful purposes to which they may be severally or jointly applicable. Nor do we limit ourselves to the exact construction of the various details, but intend to employ such equivalents therefor as fairly fall within the scope and spirit of the invention.

Having thus described our invention, what we claim, and desire to secure by Letters Patent, is—

1. An aerial tramway comprising a track-way supported along the line by a series of standards, the standards intermediate of the terminal standards having a free space between the trackway-supports for the passage of the tramway-carriage, a hauling-rope connected to the tramway-carriage, a hoisting-rope depending from the carriage, and supports for preventing the sagging of the hoisting-rope, said hoisting-rope supports spanning the free space between the trackway-supports and adapted to rest in open bearings, and a projection moving with the hauling-rope in front of the carriage, so as to engage with and successively remove the rope-supports from their bearings as the carriage moves toward them, substantially as described.

2. An aerial tramway comprising a track-way supported along the line by a series of standards, the standards intermediate of the terminal standards having a free space between the trackway-supports for the passage of the tramway-carriage, a hauling-rope connected to the tramway-carriage, a hoisting-rope depending from the carriage, and supports for preventing the sagging of the hoisting-rope, said hoisting-rope supports spanning the free space between the trackway-supports and having journals of unequal lengths adapted to rest in open bearings spaced at increasing distance apart in the path of the carriage, and a projection moving with the hauling-rope in front of said carriage, so as to engage with and successively remove the rope-supports from the open bearings as the car-

riage moves toward them and also to successively deposit them within the appropriate bearings as the carriage moves away, substantially as described.

- 5 3. An aerial tramway comprising a trackway supported along the line by a series of standards, the standards intermediate of the terminal standards having a free space between the trackway-supports for the passage 10 of the tramway-carriage, a hauling-rope connected to the tramway-carriage, a hoisting-rope depending from the carriage, and supports for preventing the sagging of the hoisting-rope, said hoisting-rope supports spanning 15 the free space between the trackway-supports and having journals of unequal lengths adapted to rest in open bearings spaced at increasing distances apart in the path of the carriage, and a projection moving with the 20 hauling-rope in front of said carriage, so as to engage with and successively remove the rope-supports from the open bearings as the carriage moves toward them and also to successively deposit them within the appropriate 25 bearings as the carriage moves away, said hauling-rope supports being further provided with rollers for the reception of the hoisting-rope and being of unequal lengths, so as to arrange themselves the more compactly upon 30 the gathering projection, substantially as described.

4. In an aerial tramway, the combination, with the trackway, the main carriage, the hauling-rope, the hoisting-rope, and its removable supports, of a gathering device therefor, 35 consisting of an auxiliary carriage mounted upon the trackway in front of the main carriage and connected to the hauling-rope, said auxiliary carriage having a gathering-horn 40 adapted to engage with and take up the removable supports in advance of the main carriage, and standards having open bearings, within which the supports are deposited or from which they are removed as the carriage passes, substantially as described.

- 45 5. In an aerial tramway, the combination, with the trackway, the main carriage, the

hauling-rope, the hoisting-rope, and its removable supports, of a gathering device therefor, consisting of an auxiliary carriage mounted 50 upon the trackway in front of the main carriage and connected to the hauling-rope, said auxiliary carriage having a gathering-horn adapted to engage with and take up the removable supports in advance of the main carriage, the auxiliary carriage being provided with a latch and actuating-cord and the hoisting-rope being provided with a catch adapted to engage said latch, substantially as described. 55

6. In an aerial tramway, a tramway-carriage 60 made up of independent frames having their proximate ends jointed to each other, so as to adapt their outer ends to swing toward each other in a vertical plane, supporting-wheels on opposite sides of the joint, and additional 65 supporting wheels directly at the joint, substantially as described.

7. In an aerial tramway, a tramway-carriage made up of independent frames having their proximate ends jointed to each other, so 70 as to adapt their outer ends to swing toward each other in a vertical plane, supporting-wheels on opposite sides of the joint, additional supporting wheels directly at the joint, and hoisting-sheaves suspended from the carriage below the supporting-wheels, substantially 75 as described.

8. In an aerial tramway, the removable supports for the hauling-rope, consisting of a cross-bar, a sheave or pulley, arms for suspending the sheave from said cross-bar, said arms being separated by an intervening space, open bearings for the cross-bar, and a tramway-carriage provided with a removing-horn 80 adapted to engage the removable supports 85 between the suspending-arms, substantially as described.

In testimony whereof we affix our signatures in presence of two witnesses.

EDMUND GIBBON SPILSBURY.
